AIR MIXER CABINET GRILL PANEL

John M. Redmond, Jr., Wichita, Kans., assignor
to The Coleman Company, Inc., Wichita, Kans.,
a corporation of Kansas

Application November 17, 1950, Serial No. 196,247

1 Claim. (Cl. 98—38)

1

This invention relates to an air mixer cabinet grill panel. The invention is particularly useful in connection with a panel or shell portion forming one face of the cabinet.

In a forced air heating system it is desired to pass highly heated air through a small conduit to an air mixer cabinet which may be installed within a room, and preferably within a wall of a room, the pipe discharging into the cabinet adjacent an inlet port of the cabinet so that room air is drawn into the cabinet for admixture with the heated air, the mixed air being finally discharged from the other end of the cabinet through an outlet port. Vane-equipped grills are secured within each of the ports. The foregoing system of heating is described in detail in the copending applications of Jack W. Kice, Serial Nos. 760,572 and 760,573, both filed July 12, 1947, both of which are now abandoned.

The attachment of separate grills to the outlet and inlet ports of the cabinet casing is unsatisfactory in that it requires a double thickness of metal within the ports, producing somewhat irregular cracks or spaces through which air is discharged, while at the same time the weight and expense of the structure are substantially increased.

I have discovered that the above difficulties can be overcome by employing a single panel or one piece front face for the cabinet in which the vanes at the spaced ports are formed integrally with the panel or face. I have further discovered that the vanes are formed with a minimum of projection beyond the cabinet face and in a very sturdy structure by anchoring reinforcing strips to the panel body and to edges of the vanes, as will be described more fully hereinafter.

An object of the present invention is to provide a unitary panel or face structure for an air mixer cabinet, the vanes being formed integrally with the panel or face. A further object is to provide a unique method for forming vanes within a panel for the securing of a sturdy structure and with a minimum of projection of the vanes beyond the face of the panel. Yet another object is to provide an elongated panel or face structure equipped with integral vanes near its end portions. Other specific objects and advantages will appear as the specification proceeds.

The invention is shown in an illustrated embodiment, by the accompanying drawing, in which—

Fig. 1 is a perspective view of a cabinet secured within a wall and equipped with panels

2

or cabinet faces embodying my invention; Fig. 2, a broken front view in elevation of the panel or cabinet face; Fig. 3, a sectional view, the section being taken as indicated at line 3—3 of Fig. 2; and Fig. 4, an enlarged broken sectional view showing a portion of the vanes integrally formed with the panel.

In the illustration given, 10 designates a panel or shell section or one-piece cabinet face. In Fig. 1, there are two of such panels or cabinet faces disposed on opposite sides of a centrally disposed shell 11. The shell 11 together with the panels 10 forms a complete enclosure and thus provides a chamber in which air may be mixed. Heated air from a furnace or other source of heated air is passed through a small pipe 12 and discharged within the cabinet provided by members 10 and 11 beyond one of the ports of the cabinet. This causes room air to be drawn into the cabinet where it is mixed with the highly heated air and the resulting mixture is discharged through the outlet port of the cabinet.

In the specific illustration given, the inlet port of the cabinet is designated by the numeral 13, while the outlet port is designated by the numeral 14. It will be understood, however, that the hot air pipe 12 may be extended through the other end of the cabinet so as to discharge air adjacent the port 14 so that it would then become the inlet port and port 13 would become the outlet port. Such structures are illustrated in the above-mentioned copending Kice applications Serial Nos. 760,572 and 760,573.

The panel 10, which is adapted to be secured over one face or side of the shell 11, is preferably formed as illustrated in Figs. 1 to 4. Each of the ports is provided by forming vanes 15 integrally with the panel 10 so that the entire panel equipped with the vanes consists of a single piece. In forming the vanes, I prefer to split the panel so as to provide the connecting neck 16 between the vane and the panel 10 at a point near the outer portion of the vane, as shown more clearly in Fig. 4. That is to say, the panel 10 is split or severed near the ends thereof along a plurality of spaced-apart parallel lines extending transversely of the panel and terminating at their outer ends on lines extending longitudinally of the panel. Along the longitudinal lines defining the ends of the vanes 15 the panel is also severed but the lines of severance are interrupted to provide the necks 16. The longitudinal severances extend from the innermost transverse severance or line to a point close to the parallel line next thereto, and then successively from the next inner line to a point

close to the following line, and so on. The panel portions provided by the lines of severance are then turned rearwardly and twist about the integral necks 16. The outer or forward edges of the vanes are substantially flush with the surface of the panel because the necks 16 are adjacent to the forward or outer edges of the vanes. At the same time, I turn rearwardly an upper portion of the panel to provide a supporting ledge 17, as shown more clearly in Fig. 3. The rearwardly-turned edges of the vanes 15 are then secured together and reenforced by the vertical strips 18, which are preferably welded or otherwise secured to the top flange or ledge 17. By anchoring the strips 18 to the rear edges of the vanes 15 and to the rigid ledge 17, a sturdy reenforcement is provided for the vanes so that they are held in true alignment while, at the same time, the front edge of the vanes is almost flush with or projects very slightly beyond the face of the panel. Any means, such as welding, brazing, soldering, etc. which will effectively secure the rear edges of the vanes to the reenforcing strips 18, while at the same time anchoring such strips to the rigid ledge 17 of the panel, may be employed.

In the assembly operation, after the shell 11 is secured within a wall, the panels 10 may be secured on either side of the wall so as to cause the room air to enter the central shell from oppositely disposed rooms and the mixed air may be simultaneously discharged from the upper end of the shell through the outlet ports 14 into both rooms. If desired, only one panel 10 may be employed and the opposite side of the shell 10 may be closed by an imperforate metal strip. By employing a panel or closure shell 10 provided with integrally-spaced grills, the full port area may be effectively employed, while a minimum of metal is utilized. Further, noise that usually attends the use of attached parts such as grills, etc. is avoided through the forming of the integral grills in the panel 10. Even though the grill vanes are provided by striking metal from the panel itself, an extremely sturdy grill structure is provided by securing each edge of the rearwardly-extending vane to a rigid flange of the panel, as above described.

In the specific illustration given, the shell which is shown within the wall space provided between the wall sections A and B, as shown more clearly in Fig. 1, and the panels or outer shell members 10 engage the outer sides of the wall sections A and B and provide closures for the open sides of shell 11. It will be understood, however, that the air mixer cabinet may be installed within a room and not within a wall recess.

While in the foregoing specification I have set forth a specific structure in considerable detail for the purpose of illustrating an embodiment of the invention, it will be understood that such details of structure may be varied widely by those skilled in the art without departing from the spirit of my invention.

I claim:

In a relatively thin-walled air mixer cabinet having in one wall thereof an elongated inlet port and spaced therefrom an elongated outlet port, each of said ports having a plurality of spaced-apart elongated vanes extending transversely thereacross and providing openings therebetween, the vanes in each of said ports being substantially parallel and having outer longitudinal edges substantially flush with the face of said wall, and neck portions integral with said wall and with said vanes at each end of said vanes and adjacent the outer longitudinal edges thereof to provide a connection between said vanes and said wall, the ends of each vane adjacent the longitudinal edges thereof being spaced from said wall.
